UNITED STATES PATENT OFFICE.

JOHN S. SHERMAN AND GEORGE H. HARMS, OF DETROIT, MICHIGAN.

DESIGN FOR AN INNER-TUBE MEMBER FOR HYDROCARBON-BURNERS.

SPECIFICATION forming part of Design No. 32,092, dated January 9, 1900.

Application filed December 17, 1898. Serial No. 699,602. Term of patent 14 years.

To all whom it may concern:

Be it known that we, JOHN S. SHERMAN and GEORGE H. HARMS, citizens of the United States, and residents of Detroit, in the county of Wayne and State of Michigan, have invented and produced a new and original Design for the Inner-Tube Member of a Hydrocarbon-Burner, of which the following is a specification, reference being had to the accompanying drawings, which form part thereof.

The burner as a whole is composed of two separable tubes, to the inner one of which this application relates.

Figure 1 is a side elevation of a tube, exhibiting our invention. Fig. 2 is a plan view of the same, and Fig. 3 is a perspective looking at that end which is toward the bottom of the sheet in Fig. 1.

The leading features of the design consist of rings disposed horizontally and vertical posts upon the outside, so that the external appearance of the structure is that of a number of horizontally-arranged rings separated by spaces, with radial flanges extending therefrom. The internal appearance of the article

is that of a number of horizontally-disposed rings separated by spaces. At the upper end of the tube is a horizontal annular flange extending beyond the rings of the tube.

A A A indicate the rings of the tube. α 30
 α α indicate the spacings between the rings.

B B B indicate the vertical posts, which extend as radial flanges from the outer periphery of the tube.

E indicates the horizontal annular flange 35 extending from the tube around its upper end.

Having described the invention, what we claim as new, and desire to secure by Letters Patent, is—

The design for the inner-tube member of 40 a hydrocarbon-burner, substantially as described.

In testimony whereof we sign this specification in the presence of two witnesses.

JOHN S. SHERMAN,
GEORGE H. HARMS.
